UNITED STATES PATENT OFFICE.

HARRY A. BONOFF, OF LOS ANGELES, CALIFORNIA.

PROTRUSION-BITE RECORDER.

Application filed December 12, 1924. Serial No. 755,436.

To all whom it may concern:

Be it known that I, HARRY A. BONOFF, a citizen of the United States, residing at Los Angeles, in the county of Los Angeles and 5 State of California, have invented new and useful Improvements in Protrusion-Bite Recorders, of which the following is a specification.

This invention relates to improvements in 10 protrusion bite recorders, which are used by dentists in properly obtaining the inclination of the condyle paths for the setting up of artificial teeth.

Heretofore protrusion bite recorders have 15 been employed for determining the inclination of the condyle path, which recorders may only record when the patient opens his jaw, forces it forward, and then lifts it so as to engage the upper bite block. This 20 movement of the lower jaw is unnatural and consequently does not properly record the positions between the upper and lower bite blocks so that when the recorder is applied to an articulator, the inclination of the condyle path as determined by the articulator 25 is not accurate.

It is therefore an object of this invention to provide a protrusion bite recorder which 30 will enable the patient to move his lower jaw forward while the upper and lower bite blocks are in approximate engagement, and to provide means for securing the upper and lower bite blocks in any position which they 35 may assume.

With the foregoing and other objects in 40 view which will be made manifest in the following detailed description and pointed out in the appended claims, reference is had to the accompanying drawings for an illustrative embodiment of the invention, wherein:

Figure 1 is a perspective view of the improved protrusion bite recorder;

Fig. 2 is a top plan view of the bottom 45 member or plate of the recorder;

Fig. 3 is a vertical section taken substantially on the line 3—3 of Fig. 2;

Fig. 4 is a top plan view of the upper 50 plate or member of the recorder;

Fig. 5 is a side elevation of the member shown in Fig. 4;

Fig. 6 is a vertical section, supposedly 55 through a patient's mouth, showing the bite blocks and recorder in position therein; and

Fig. 7 is a side elevation and a more or less 60 diagrammatical view of an articulator in connection with which the improved protrusion bite recorder is adapted to be used.

Referring to the accompanying drawings 65 wherein similar reference characters designate similar parts throughout, it is believed that in order to understand the advantages of the improved protrusion bite recorder, a brief description of the steps employed in making a dental plate is necessary. Referring to Fig. 6, a mold is first taken of the top T of the patient's mouth and a similar mold is taken of the bottom or lower jaw B. A suitable cementitious material is then 70 poured into the molds taken so as to form a counterpart similitude of the top and bottom of the patient's mouth. When this is done a base plate 10 is provided which snugly fits against the top of the patient's mouth, and a similar base plate is provided which 75 fits upon the bottom of the patient's mouth. Wax as indicated at 12 is then built upon the base plate 10 and wax 13 is built upon the base plate 11. The base plate 10 with the wax 12 which takes the place of teeth 80 constitutes an upper bite block, and the base plate 11 together with the wax 13, which wax takes the place of the lower teeth, constitutes a lower bite block. These bite blocks may then be mounted upon a face bow or 85 similar device, as disclosed in my prior Patent, No. 1,497,259, issued June 10, 1924. In this manner, the central position between the jaws or top and bottom of the patient's mouth may be determined with respect to 90 the condyle when the lower jaw is in normal rest position.

When the face bow together with the bite blocks is applied to an articulator, as disclosed in Fig. 7, the counterparts of the top 95 and bottom of the patient's mouth may be located with respect to one point on the patient's condyle path. As shown in Fig. 7, the articulator consists of a base 14 having standards 15, within which are rotatably 100 mounted discs 16 having slots 17. An upper member 18 carries balls or pins 19 which are slidably in the slots 17. When the face bow is so applied, the balls or pins 19 occupy a position in the slots 17, which is adjacent 105 the center of the discs 16. The bite blocks carried by the face bow assume a definite relation with respect to the centers of the

discs 16. The casts indicated at 20 and 21 of the top and bottom of the patient's mouth are then caused to fit within the base plates 10 and 11 respectively. The cast 21 of the 5 lower part of the patient's mouth is then secured to the base 14 as by plaster of Paris 22, or the like; and the cast 20 of the roof of the patient's mouth is secured to the upper member 18 as by plaster of Paris 23. In 10 this manner, the casts 20 and 21 bear a definite relation with respect to the discs 16, and when the pins 19 are in the ends of the slots 17 adjacent the centers of the discs 16, the upper and lower casts 20 and 21 will bear a 15 relation to each other corresponding to the top and bottom of the patient's jaws when in normal position.

In determining the inclination of the condyle path, it is necessary to record the 20 relation which the jaw or mandible bears to the patient's upper jaw when the lower one is protruded. After the casts 20 and 21 are mounted upon the articulator, the bite blocks are then mounted upon the protrusion bite 25 recorder, as disclosed in Fig. 1. This recorder consists of upper and lower plates 25 and 26, which are preferably U-shaped in form. The upper plate 25 carries an arm or stem 27 upon which is rotatable and slid- 30 able a split clamping collar 28. A similar clamping collar 29 is secured to the clamping collar 28 by means of a threaded bolt 30 which extends through both of the adjacent ends of the clamping collar 29 and through 35 the adjacent ends of the clamping collar 28. A wing or thumb nut 31 is threaded on to the bolt 30 and upon tightening causes the adjacent ends of both of the clamping collars 28 and 29 to be drawn together. The clamping collar 29 is axially slidable and rotatable upon a pin 32. When the wing nut 31 is tightened, the arm 27 can neither rotate in nor slide in the clamping collar 28, and the clamping collar 29 can neither rotate up- 40 on or axially slide upon the pin 32.

The lower plate 26 carries an arm 33 upon which is rotatable a clamping collar 34, which clamping collar is similar in construction to the clamping collars 28 and 29. 50 The pin 32 is rigidly secured to the clamping collar 34. A bolt 35 extends through the adjacent ends of the clamping collar 34 and is adapted to be tightened by a wing nut 36, which wing nut upon tightening the bolt 55 35 prevents the clamping collar 34 from rotating upon the arm 33.

Suitable prongs 37 are formed on the 60 plate 25 and are adapted to be forced into the wax 12 of the upper bite block, as indicated in Fig. 6. Similar prongs 38 are formed upon the lower plate 26 and are adapted to be forced into the wax 13 upon the lower bite block. Portions of the lower 65 plate 26 are struck out, as indicated at 39, so as to provide leaf springs which engage

the upper plate 25 so as to normally urge the plates into spaced relation with respect to each other. When the upper and lower bite blocks are mounted upon the protrusion bite recorder by forcing the prongs 37 and 70 38 into the wax 12 and 13, the bite blocks and bite recorder are then inserted into the patient's mouth. The patient by closing his mouth may force the bite blocks toward each other, as indicated in Fig. 6, so that the 75 plates 25 and 26 will be disposed adjacent each other against the action of the leaf springs 39. While in this position, the patient may move his lower jaw forward while maintaining the plates 25 and 26 in contact 80 with each other. This movement is a natural movement as distinguished from the devices heretofore provided, where the patient necessarily first dropped his lower jaw, then forced it forwardly, and then caused it to 85 be drawn upwardly. After the patient has forced his lower jaw forwardly with the plates 25 and 26 in contact, the thumb nuts or wing nuts 31 and 36 are both tightened, and the plates 25 and 26 are thus maintained 90 in adjusted position with respect to each other.

The recorder with the bite blocks therein is then transferred to the articulator. The lower bite block which is mounted upon the 95 lower plate 26 is then placed back upon the cast 21. Because of the changed relation between the upper and lower bite blocks, the cast 20 will not fit into the upper bite block until the upper member 18 has been 100 manipulated. When the cast 20 is forced or caused to fit within the upper bite block or base plate, the balls or pins 19 will be caused to assume a position within the slots 17 similar to that shown. The position of 105 the slots 17 within the discs 16 then indicates the inclination of the condyle path of the patient. Suitable set screws 40 may be used for maintaining the discs 16 in such position, and in this manner the articulator 110 may be easily and accurately set to indicate the inclination of the condyle path of the patient.

Because of the fact that the clamping collars 29 and 34 are rotatable as well as slide- 115 able upon their respective members, the plates 25 and 26 may assume any position with respect to each other that is necessary in recording the position of the mandible while protruded, and if the lower jaw has 120 merely a point of engagement with the upper jaw when in protruded position, the leaf springs 39 prevent the upper and lower bite blocks from disengaging the patient's mouth; in other words, the upper and lower 125 bite blocks will be always maintained in engagement with the top and bottom of the patient's mouth.

It will be understood that various changes in the detail of construction may be made 130

without departing from the spirit or scope of the invention as defined by the appended claims.

I claim:

5. 1. A protrusion bite recorder comprising a pair of U-shaped plates, an arm carried by one of said plates, a clamping collar rotatable upon said arm, means for clamping said collar upon said arm, a pin carried by said 10 clamping collar, a second clamping collar rotatable upon and adapted to be clamped upon said pin, a second arm carried by the other plate, a third clamping collar pivoted to said second clamping collar and rotatable 15 upon said second arm, and means for clamping said third clamping collar against rotation with respect to said second clamping collar and said second arm.
2. A protrusion bite recorder comprising a 20 pair of U-shaped plates, an arm carried by one of said plates, a clamping collar rotatable upon said arm, means for clamping said collar upon said arm, a pin carried by said clamping collar, a second clamping collar rotatable upon and adapted to be clamped upon said pin, a second arm carried by the other plate, a third clamping collar pivoted to said second clamping collar and rotatable 25 upon said second arm, and means for clamping said third clamping collar against rotation with respect to said second clamping collar and said second arm, there being prongs formed upon said plates for securing a bite block thereto.
3. A protrusion bite recorder comprising 30 a pair of U-shaped plates, an arm carried by one of said plates, a clamping collar rotatable upon said arm, means for clamping said collar upon said arm, a pin carried by said clamping collar, a second clamping collar rotatable upon and adapted to be clamped upon 35 said pin, a second arm carried by the other plate, a third clamping collar pivoted to said second clamping collar and rotatable upon said second arm, and means for clamping said third clamping collar against rotation with respect to said second clamping collar and said second arm, and spring means interposed between said plates for urging said

plates into spaced relation with respect to 50 each other.

4. A protrusion bite recorder comprising a pair of plates, an arm secured to each plate, a pin connecting said arms, means permitting said pin to rotate about one of said 55 arms, means permitting the other arm to slide axially with respect to said pin and to rotate with respect thereto, and means for clamping said pin in any adjusted position with respect to said arms. 60

5. A protrusion bite recorder comprising a pair of plates, an arm secured to each plate, a pin connecting said arms, means permitting said pin to rotate about one of said 65 arms, means permitting the other arm to slide axially with respect to said pin and to rotate with respect thereto, means for clamping said pin in any adjusted position with respect to said arms, and prongs formed upon said plates for securing a bite block 70 thereto.

6. A protrusion bite recorder comprising a pair of plates, an arm secured to each plate, a pin connecting said arms, means permitting said pin to rotate about one of said 75 arms, means permitting the other arm to slide axially with respect to said pin and to rotate with respect thereto, means for clamping said pin in any adjusted position with respect to said arms, and springs struck out 80 from the body of one of said plates adapted to engage the other plate so as to urge said plates into spaced relation with respect to each other.

7. A protrusion bite recorder comprising 85 two members, an arm rigidly connected to each member, a pin, and clamping means connecting each arm to the pin, said clamping means permitting each arm to rotate upon its own axis relatively to the pin and 90 permitting one of the arms to swing about the axis of the pin, said clamping means also permitting one of the arms to slide upon its axis relatively to the pin.

In testimony whereof I have signed my 95 name to this specification.

HARRY A. BONOFF.
